COLLAPSIBLE CLOTHES DRIER

Rosario J. Rizzo, Elmont, N. Y., assignor to J. F. D. Mfg. Co., Inc., Brooklyn, N. Y., a corporation of New York

Application January 10, 1956, Serial No. 558,264

1 Claim. (Cl. 211—179)

My invention relates to improvements in collapsible clothes driers of the type in which a row of clothes lines are mounted between hangers with the clothes lines extending in parallel directions.

In conventional clothes driers of this type, the hangers are straight in their extended or assembled positions, so that the clothes lines are arranged along a common horizontal plane. Such arrangement makes it difficult for the user to reach the innermost clothes lines adjacent the center post, the outermost clothes lines being at the same horizontal level and obstructing access to the inner lines.

It is the principal object of my invention to provide a clothes drier of the type described in which the hangers are each made of a pair of hanger arms arranged in the shape of a V, and each hanger arm being inclined upwardly from its inner end to its outer end, so that the inner clothes lines are readily accessible to the user without the necessity of squatting or stooping. Such V-shaped arrangement also provides a greater effective drying area for the clothes hung on the lines.

Another object of the invention is the provision of a clothes drier of the type described in which the drier is provided with unique brackets or hinges arranged to bring the hangers automatically to their proper V-shaped position when the drier is extended.

Still another object of the invention is the provision of a clothes drier of the type described in which a plurality of support members are arranged in such manner as to cause the drier parts to be smoothly, easily and conveniently collapsed and extended with the expenditure of minimum energy on the part of the user.

A further object of the invention is the provision of a clothes drier of the type described in which the drier arms fold upwardly and are not lowered relative to the center post when the drier is collapsed, so that the clothes lines hang evenly without tangling in the folded position of the drier, and cannot pass below the bottom of the center post.

Other objects and advantages of my invention will be apparent in the course of the following specification when taken in connection with the accompanying drawings, in which:

Fig. 1 is a top plan view of a clothes drier made according to the invention, the drier being shown in extended operative position with the top cap of the center post removed for clarity of illustration;

Fig. 2 is a side elevational view of the clothes drier of Fig. 1 in extended position, with portions of the clothes line broken away and the center post also broken away for convenience;

Fig. 3 is an end elevational view as viewed from the left side of Fig. 2;

Fig. 4 is a side elevation similar to Fig. 2, but showing the drier in its fully collapsed or folded condition. In this view all clothes lines except the lowermost line are broken away to reveal inner structure;

Fig. 5 is an end elevation similar to Fig. 3, but showing the drier in collapsed position;

2

Fig. 6 is an enlarged perspective view of one of the brackets of the drier showing the manner of attachment of its associated parts;

Fig. 7 is a section taken along plane 7—7 of Fig. 6; and

Fig. 8 is a section taken along lines 8—8 of Fig. 3.

Referring in detail to the drawings, in which like reference numerals denote like parts in all of the figures, there is shown a clothes drier made according to my invention and including a center post 10 which may be provided with a base (not shown) or suitable means for anchoring the post in upright vertical position in the ground. The center post 10 may be tubular and provided with the usual top rubber cap 28 for closing off its top end.

15 The clothes drier also includes a pair of hangers 11 and 12 disposed in V-shaped form in the extended position of the drier, as shown in Fig. 3. The hangers 11 and 12 are carried by support rods 14 and 15 so that they extend parallel to each other, spaced on opposite sides of the center post 10. A plurality of flexible clothes lines 16 are mounted parallel to each other between the hangers 11 and 12.

An elongated sleeve 17 is slidably mounted on the center post 10. Sleeve 17 has adjacent its bottom end 25 a pair of aligned ears 18 projecting from one side thereof and a second pair of ears 19 projecting from the opposite side thereof. The ends of support rods 14 and 15 extend between the respective ears 18 and 19, and are pivoted thereto by pivot pins 20 extending between said 30 pairs of ears.

The opposite ends of the support rods 14 and 15 each carry a bracket 21, one of said brackets being shown in detail in Fig. 6. The bracket 21 comprises a central section of inverted U-shape defining a transverse channel 35 22 which is open at its bottom end. Respective pairs of spaced ears 23 extend from opposite sides of said central section.

The brackets 21 are pivotally carried at the outer ends of support rods 14 and 15 by means of pivot pins 24 extending between the side walls of the U-shaped central bracket section and through the end portion of the support rods 14 and 15, as shown in Fig. 7.

The hangers 11 and 12 are formed of respective pairs of hanger arms 11a, 11b and 12a, 12b, of identical lengths. As shown in Fig. 1, the hanger arms 11a and 11b are 45 pivoted between the opposed pairs of ears 23 of one bracket 21, while the hanger arms 12a and 12b are pivoted between the ears of the other bracket 21.

The manner of mounting the hanger arms on brackets 21 is shown clearly in the detailed view of Fig. 6 which 50 illustrates the bracket carried by support rod 14. It may be seen that the ends of hanger arms 11a and 11b are mounted on pivot pins 25 extending between the inner end portions of the pairs of bracket ears 23, that is, adjacent the central U-shaped bracket section. Stop pins 26 are 55 mounted between the pairs of bracket ears 23 at the outer ends thereof and in horizontal alignment with the pivot pins 25. It will be noted that in the extended position of the drier, the pivot pins 25 and stop pins 26 are horizontally disposed. The stop pins 26 are so located 60 that they hold the respective hanger arms 11a, and 11b and 12a, 12b in upwardly inclined positions relative to the brackets 21 so that the hangers 11 and 12 in extended operative position assume the V-shape shown in Fig. 3. This is an important feature of the drier.

65 The hangers 11 and 12 are supported by four support arms 30, the inner ends of which are pivotally mounted on projecting ears 31 of a pair of bracket members 32, by pivot pins 33. The bracket members 32, as shown in Fig. 8, are fixed in diametrically opposed relationship to the upper end of sleeve 17 by rivets 27.

The outer ends of the four support arms 30 are connected to intermediate portions of the respective hanger arms 11a, 11b; 12a and 12b, as shown in Figs. 1 and 3 by means of swivel joint connections consisting of pairs of interconnected eye bolts 34 and 35.

The support arms 30 are in turn supported by four brace arms 36 mounted on a pair of brackets 37 fixed rigidly to the top end of center post 10 by rivets 38. Each bracket 37 has a pair of projecting ears 39 to each of which one of the brace arms 36 is pivotally connected by a pivot pin 40. The opposite ends of each brace arm 36 extend between a pair of plates 41 fixedly mounted adjacent the center of each support arm 30 and is pivoted between said pair of plates 41 by a pivot pin 42.

Figs. 4 and 5 show the slidable collar 17 in its lowermost position, the drier being in its collapsed or folded condition. The brace arms 36 have pivoted downwardly until they are parallel to and proximate to the post 10. The support arms 30 and support rods 14, 15 have pivoted upwardly and are substantially parallel to center post 10. In addition, the hanger arms 11a, 11b and 12a, 12b have pivoted upwardly and inwardly toward each other and are upstanding from the ends of support rods 14 and 15, so that the collapsed drier is in compact form for convenient transporting or storage. As shown in Fig. 4, the hangers 11 and 12 are slightly inclined toward each other in their collapsed position.

When it is desired to bring the drier to its assembled, extended position, it is merely necessary to slide the sleeve 17 upwardly upon the center post 10. This upward movement of sleeve 17 causes the support arms 30 to move upwardly and also to pivot downwardly because of their pivoted connection to the fixed brace arms 36. The downward pivoting of the support arms 30 in turn lowers the hanger arms 11a, 11b, 12a and 12b, at the same time causing them to separate and also causing downward pivoting of support rods 14 and 15, which moves the hangers 11 and 12 outwardly away from center post 10.

Once the sleeve 17 is started in its upward movement and the hangers 11 and 12 are moved away from center post 10, the weight of said hangers 11 and 12 on the ends of support rods 14, 15 and support arms 30, cause these support rods and arms to pivot downwardly, which downward pivoting raises the sleeve 17. As the drier approaches its fully extended position, the sleeve 17 is thus being raised by the weight of the hangers 11 and 12. In the fully extended position of the drier shown in Figs. 1, 2 and 3, upward movement of the sleeve is halted by a stop pin 43 fixed to the center post 10.

In the extended position of the drier, the support rods 14 and 15 are axially aligned and are substantially horizontal, the brackets 21, and their pivot pins 25 and stop pins 26 being also horizontally disposed. The support arms 30 are slightly downwardly inclined from the sleeve 17 to the hangers 11 and 12, and the brace arms 36 are sharply inclined downwardly.

In this extended position, as has been previously indicated, the stop pins 26 of brackets 21 locate the hanger arms in angular positions relative to said brackets 21, so that the hangers 11 and 12 assume the V-shape shown in Fig. 3. Such V-shape locates the clothes lines 16 axially parallel to each other, but at stepped horizontal levels. This arrangement presents a distinct advantage in contrast to the conventional driers in which the clothes lines are parallel and horizontally aligned, making it difficult for the user to reach the inner lines, that is, the lines adjacent the center post. In such conventional driers, the outer lines invariably strike the user's face or head as the user reaches for the inner lines, necessitating stooping and groping for gaining access to the center of the drier. In the drier of the present invention, the V-shaped arrangement of the hangers provides easy accessibility to the inner clothes lines 16 and also to the sleeve 17 (for

extending or collapsing the drier), even when the user is in a comfortable, upright standing position. The stepped arrangement of the clothes lines also locates the drying clothes in a vertically staggered position, increasing the effective drying area and decreasing the drying time.

It will be noted from a comparison of Figs. 3 and 5, that the brackets 21 are in substantially the same vertical level at both the extended and collapsed positions of the drier. The hangers 11 and 12 therefore fold upwardly relative to the post 10 rather than being drawn down along the post or being rotated about its central axis as in driers presently on the market. Consequently, when the ends of the clothes lines 16 are drawn closer to each other when the drier is collapsed, the lowermost line 16, as shown in Fig. 6, hangs downwardly only a short distance relative to the post 10, its bottom end terminating well short of the bottom of post 10. In many conventional driers, the collapsed clothes lines hang below the bottom of the central post so that they either drag on the ground, or, if the post is not mounted, swing over to the opposite side below the bottom of the post, causing tangling and snarling of the lines with each other and with the center post.

In addition, the uniformly staggered arrangement of the ends of clothes lines 16 in the collapsed condition of the drier, causes the collapsed lines 16 to hang freely, independently and neatly so that they readily assume their distended form when the drier is extended without tangling or snarling with each other.

While a preferred embodiment of my invention has been shown and described herein, it is obvious that numerous omissions, changes and additions may be made without departing from the spirit and scope of the invention.

What is claimed is:

A collapsible clothes drier comprising a center post adapted to be maintained in an upright vertical position, a sleeve vertically slidable on said post, a pair of support arms pivoted on opposite sides of said sleeve at the upper end thereof, pairs of support rods pivoted on opposite sides of said sleeve at the lower end thereof with a respective support rod located between each respective pair of support arms, brace arms each pivoted to the upper end of said post at one end of said brace arm and to the intermediate portion of a respective support arm at the other end of said brace arm, a pair of brackets, each said bracket comprising a central yoke portion pivoted to the free end of a respective support rod so as to be turnable relative thereto about an axis which extends horizontally and also laterally at right angles to said support rod, pairs of spaced and parallel ears projecting laterally and vertically from respective opposite sides of said central yoke portion, and a horizontal stop pin connecting between each pair of ears adjacent the free ends thereof, a hanger mounted on each bracket, each hanger comprising a pair of hanger arms, each of said hanger arms being pivotally mounted at one of its ends between a respective pair of bracket ears inwardly of said stop pin and so as to be turnable about a horizontal axis which is transverse to said ears, said support arms and said brace arms cooperating with said sleeve and said support rods for bringing said hangers to an extended position when said collar is raised on said center post and a collapsed position when said collar is lowered on said center post, said support rods being disposed substantially horizontally in said extended position with the hangers spaced on opposite sides of said center post, said support rods being disposed substantially parallel to and adjacent said center post in said collapsed position, with the hanger arms upstanding therefrom, each said hanger arm abutting its stop pin and being upwardly outwardly inclined when in extended position, with the extended hangers horizontally aligned.
